UNITED STATES PATENT OFFICE.

GEORGE M. RAND, OF BROCKTON, MASSACHUSETTS.

MAILING-FOLDER.

1,106,058.

Specification of Letters Patent.

Patented Aug. 4, 1914.

Application filed October 30, 1913. Serial No. 798,205.

To all whom it may concern:

Be it known that I, GEORGE M. RAND, a citizen of the United States, residing at Brockton, in the county of Plymouth and 5 State of Massachusetts, have invented new and useful Improvements in Mailing-Folders, of which the following is a specification.

This invention relates to improvements in 10 mailing folders and has for its object to provide a folder having flaps adapted to be folded back one against the other and to contain a post card bearing the address of the person to whom the folder is to be sent with 15 all of said card, with the exception of the portion containing said address, concealed between said flaps, while means are formed on one of said flaps adapted to interlock with the other of said flaps to retain said 20 folder in its folded state with or without said card therein, said retaining means also constituting positioning means for said card.

The invention consists in the combination and arrangement of parts whereby the above 25 objects and certain other objects hereinafter appearing may be attained, as set forth in the following specification and particularly pointed out in the claims.

Referring to the drawings: Figure 1 is 30 a plan view of a folder embodying my invention folded and locked and in readiness to be sent through the mail. Fig. 2 is a perspective view of the folder partially folded and with a card shown in connection 35 therewith. Fig. 3 is a plan view of a modified form of folder with a portion of the outermost flap thereof broken away and shown in section.

Like numerals refer to like parts through 40 out the several views of the drawings.

In the drawings, 4 is a folder formed of sheet material and comprising an intermediate portion 5 and flaps 6 and 7 formed integral therewith and upon opposite edges, 45 preferably the bottom edge 8 and the top edge 9 respectively. The bottom flap 6 is substantially equal in width to the intermediate portion 5 and is adapted to be folded back against said intermediate 50 portion, while the top flap 7 is arranged to fold against said bottom flap and is substantially shorter than said bottom flap. Means are provided for securing said flaps in their folded positions and consist 55 preferably of tongues 10 formed upon the

inner flap 6 by partially detaching portions of the material constituting said flap and these tongues are adapted to engage or interlock with the outermost flap 7 through slits 11 arranged longitudinally of said flap 60 and adjacent the free edge thereof. The tongues 10 are preferably formed from the material constituting said flap 6 by slitting said material from points 12 at substantial distances from the edge 8 toward the free 65 edge 13 of said flap, thence inwardly along a line 14 for a short distance and thence downwardly along a line 15 parallel to the lines 12 and terminating in semi-circular slits 16 which are also at substantial 70 distances from the edge 8. A post card 17 is adapted to be inserted between the flaps 6 and 7, the upper edge 18 of said card engaging the crease 19 of said flap 7, thus positioning said card vertically in one direction. To position the card vertically in the opposite direction the lower corners of said card are adapted to project into the slits forming said tongues 10, the lower edge 20 of said card engaging the curved portions 16 80 of said slits while the ends of said card engage the edges formed by the slits 12 and position said card laterally relatively to said folder. The card 17 is substantially wider than the flap 7 and consequently projects below the free edge 21 thereof exposing a portion of said card to view, while upon the exposed portion of said card is printed or written the name of the person or persons to whom the folder is to be sent. 90

In Fig. 3 I have illustrated a folder similarly constructed in every respect to the folder illustrated in Figs. 1 and 2, with the exception that the tongues 10' are provided at their upper inner corners with projections 95 22 which, when said tongues are inserted in the slits 11', extend inwardly substantially beyond the ends 23 of said slits and more firmly and positively lock said tongues in engagement with the flap 7'. 100

By providing tongues, as hereinbefore described, on one of the flaps and slits in the other flap adapted to be engaged by said tongues, said flaps may be locked in their folded positions independently of the post card and without necessitating the use of clips or fasteners at the ends of said folders, or in other words said flaps are adapted to interlock with each other and retain said folder in its folded state. 110

Having thus described my invention what I claim and desire by Letters Patent to secure is:

1. A mailing folder having, in combination, an intermediate portion, flaps formed upon the top and bottom edges of said intermediate portion adapted to be folded back one against the other, the outermost of said flaps being shorter than the inner flap, 5 a card arranged between said flaps adapted to extend beyond the free edge of said outermost flap, tongues formed by slitting said inner flap adapted to interlock with said outermost flap to lock said flaps in their 10 folded positions, the slits forming said tongues adapted to receive the lowermost corners of said card and position said card laterally relatively to said folder and vertically in one direction, with a portion of 15 said card exposed to view, the top of said card adapted to engage the crease of said outermost flap to position said card vertically in the opposite direction.

2. A mailing folder having, in combination, an intermediate portion, flaps formed upon the top and bottom edges of said intermediate portion adapted to be folded back one against the other, the outermost of said flaps being shorter than the inner flap, a 20 card arranged between said flaps adapted to engage the crease of said top flap and to project a substantial distance below the free edge of said top flap, said top flap provided with longitudinally disposed slits adjacent 25 the free edge thereof, and tongues formed by slitting the material constituting said bottom flap, said tongues adapted to interlock with the slits in said top flap to retain 30 said flaps in their folded positions, the slits 35 in said bottom flap terminating at substantial distances from the crease of said bottom flap and adapted to receive the lower corners of said card and position said card to 40 prevent lateral and downward movement 45 thereof.

3. A mailing folder having, in combination, an intermediate portion, flaps formed at opposite edges of said intermediate portion adapted to be folded one against the 50 other, the outermost of said flaps being substantially shorter than the inner flap and

provided with longitudinally arranged slits, tongues formed on said inner flap adapted to interlock with said outermost flap through said slits, said tongues being formed 55 by slitting said inner flap from points substantially removed from the crease of said flap toward its free edge, thence inwardly longitudinally of said flap, and toward the crease thereof to points substantially nearer 60 said crease than said starting points, and a card arranged between said flaps adapted to engage the crease of said outermost flap and project beyond the free edge thereof, the lowermost corners of said card adapted 65 to project into the slits forming said tongues, whereby said card will be positioned longitudinally and transversely relatively to said folder with a portion thereof 70 exposed to view.

4. A mailing folder having, in combination, an intermediate portion, flaps formed at opposite edges of said intermediate portion adapted to be folded one against the other, the outermost of said flaps being substantially shorter than the inner flap and provided with longitudinally arranged slits, tongues formed on said inner flap adapted to interlock with said outermost flap through said slits, said tongues being formed 75 by slitting said inner flap from points substantially removed from the crease of said flap toward its free edge, thence inwardly longitudinally of said flap, and toward the crease thereof to points substantially nearer 80 said crease than said starting points, and terminating in semicircular slits, and a card arranged between said flaps adapted to engage the crease of said outermost flap and project beyond the free edge thereof, the 85 lowermost corners of said card adapted to project into the slits forming said tongues with the lower edge of said card engaging 90 said semicircular slits.

In testimony whereof I have hereunto 95 set my hand in presence of two subscribing witnesses.

GEORGE M. RAND.
